Primary Examiner — Christy Nemeth

(57) **CLAIM**

The ornamental design for an energy storage device as shown and described.

DESCRIPTION

1. Energy storage device

1.1 : Front

1.2 : Back

1.3 : Left

1.4 : Right

1.5 : Top

1.6 : Bottom

1.7 : Perspective

1.8 : Perspective

FIG. 1.1 is a front view of an energy storage device; FIG. 1.2 is a rear view thereof; FIG. 1.3 is a left side view thereof; FIG. 1.4 is a right side view thereof; FIG. 1.5 is a top view thereof; FIG. 1.6 is a bottom view thereof; FIG. 1.7 is a front perspective view thereof; and FIG. 1.8 is a rear perspective view thereof; The broken lines shown in the drawings depict portions of the energy storage device that form no part of the claimed design.
